UNITED STATES PATENT OFFICE.

JOHN TOOMEY, OF COSCOB, CONNECTICUT.

MEADOW-DITCHING TOOL.

Application filed April 19, 1924. Serial No. 707,753.

To all whom it may concern:

Be it known that I, JOHN TOOMEY, a citizen of the United States, and a resident of Coscob, in the county of Fairfield and State 5 of Connecticut, have invented a new and Improved Meadow-Ditching Tool, of which the following is a full, clear, and exact description.

This invention has relation to earth working tools and has particular reference to a meadow ditching tool which is especially employed in mosquito extermination work.

The principal object of the invention resides in the provision of a ditching tool of 15 the character set forth which is operable by one man for the formation of ditches or trenches in meadow land.

The invention furthermore comprehends a ditching tool which is extremely simple, 20 yet strong and durable in its construction; which is inexpensive to manufacture and produce; which is highly efficient in its purpose; and which is light in weight and capable of disassembly for convenience in 25 handling and carrying when not in use.

With the above recited and other objects in view, the invention resides in the novel construction set forth in the following specification, particularly pointed out in the 30 appended claims and illustrated in the accompanying drawings, it being understood that the right is reserved to embodiments other than those actually illustrated herein to the full extent indicated by the general meaning of the terms in which the 35 claims are expressed.

In the drawings—

Figure 1 is a front view of a tool constructed in accordance with the invention.

Fig. 2 is a side view thereof.

Fig. 3 is a top plan view with parts in section to disclose the underlying structure.

Fig. 4 is a diagrammatic view illustrating the manner in which the trench or ditch is formed by the tool.

Referring to the drawings by characters of reference, the tool includes a cutting head designated generally at 10 which is preferably constructed from a length of steel bent in U-form to provide a pair of spaced vertical parallel blades 11 joined at their upper end by a bight 12. The blades 11 are formed at their free ends with downwardly converging oppositely disposed cutting edges 13, the upper end of which edges terminate at an appropriate distance below

the bight or connecting portion 12 whereby the head is formed with parallel side edges 14 of a width approximately equal to the distance between the blades 11. The bight 60 12 and the upper portion of the blades 11 are reinforced by a rib or strip 15 disposed exteriorly thereof. A continuous reinforcing band 16 is disposed between the blades 11, the lower edge 17 of said band being in alignment with the juncture of the cutting edges 13 and parallel side edges 14. A relatively narrower external continuous reinforcing band 18 embraces the blades 11 and the reinforcing rib or strip 15, the 70 upper edge of the band 18 being parallel with the upper edge of the band 16. The band 16 is provided with axially aligned apertures 19 immediately below the lower edge of the exterior band 18 for a purpose 75 to be hereafter set forth. The band 16, the blades 11 and the reinforcing rib or strip 15 are provided with aligned apertures 20 immediately below the lower edge of the external band 18 for receiving therethrough a rod 21 which is designed to project outwardly at its opposite ends from the side faces of the blades to provide a transverse foot rest on each side of the tool head. In order to retain the rod 21 in place against lateral and rotary movement, a pair of substantially semi-circular embracing lugs 22 project laterally from the band 18 and have threaded therethrough set screws 23. A bail-shaped handle 24 providing resilient 80 side legs 25 which are connected at their upper ends by a bight 26 is provided and the lower free ends of the side legs 25 are turned inwardly to form attaching terminals 27 for the handle member. The attaching terminals 27 are designed to be inserted in the aligned apertures 19 in the band 16 and in order to provide means for retaining said terminals in the openings 19 85 a longitudinally extending strip 28 is attached to the under side of the bight 12 of the tool head, the opposite ends 29 thereof projecting forwardly and rearwardly of the bight. One side edge of each end 29 is formed with a bayonet slot 30 which receives and maintains the legs 25 against their normal inherent tendency to separate, thus retaining the attaching terminals 27 positioned within the openings 19. 100

In use and operation of the tool the operator after attaching the handle 24 forces the lower pointed free ends of the 110

blades 11 into the ground by standing upon the foot rest afforded by the rod 21 so that the operator's weight is impinged on the tool head. When the blades have been inserted into the ground, the operator by grasping the handle 24 and reciprocating the same to swing the blades 11 forwardly and rearwardly eventually cuts the ground or turf the full width of the widest portion 5 of the blade. It should be noted that the lower forward edge 17 of the band 16 contacts with the ground or turf and marks the same. The operator then withdraws the tool from the ground and inserts the same at a right angle to the first mentioned cuts, using the mark made by the edge 17 as a gage for the insertion of the tool transversely to the ditch which is being formed where the operation is repeated. It will 10 thus be seen that by a succession of longitudinal and transverse cuts as illustrated in the diagram in Fig. 4, a number of squares of the ground or turf will be cut away, after which a suitable tool is employed for 15 severing the blocks or squares at the bottom and removing the same to produce the ditch. It will be further observed that when the tool is to be carried or transported, the handle 24 may be readily removed and if desired the rod 21 withdrawn for 20 the purpose.

I claim:

1. A one-man meadow ditching tool comprising a cutting head constructed from a length of material bent upon itself in inverted U-form to provide spaced parallel cutting blades connected at their upper end by a bight, a transversely disposed rod extending through the blade portions of the 35 head adjacent their connecting bight to

provide a foot rest projecting outwardly beyond the outer sides of the blades, means for retaining the foot rest against axial or rotary movement, a detachable handle carried by the head, and means arranged transversely of the blades for marking the ground, as and for the purpose specified. 45

2. In a meadow ditching tool a cutting head including spaced parallel cutting blades connected at their upper ends by a bight and having downwardly converging oppositely disposed cutting edges, inner and outer reinforcing bands embracing the blades, the inner band having apertures, a bail-like handle having inwardly projecting trunnions at the free ends of its legs, means carried by the bight of the cutting head and engageable with the legs of the handle for retaining the same in upwardly projecting relation to the cutting head, and laterally projecting foot rests carried by the cutting head for impinging thereon the operator's weight whereby to force the blade into the ground and to retain the same in place while permitting of oscillation of the head by the handle to make the cut of a uniform width throughout its length. 50

3. In a meadow ditching tool a forked cutting head defining a pair of parallel blades each having downwardly converging cutting edges at the opposite sides thereof, foot rests on the cutting head and a rigid handle projecting upwardly from the cutting head whereby the operator may 55 stand upon the foot rests and oscillate the cutting head to cause the cuts to be made of a uniform width throughout their depth as and for the purpose specified. 60

JOHN TOOMEY.
